CLAIM

The ornamental design for a portable interface console for monitoring of gas delivery systems, as shown and described.

DESCRIPTION

FIG. 1 is a top, front and left side perspective view of a portable interface console for monitoring of gas delivery systems showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom plan view thereof; and,

FIG. 7 is a top plan view thereof.
